UNITED STATES PATENT OFFICE.

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE.

PRINTED PAPER WEB.

Original application filed November 4, 1924, Serial No. 747,726. Divided and this application filed March 6, 1926. Serial No. 92,656.

This invention relates to printed forms of bills and more particularly to a form in which certain portions may be readily detached from the body of the web carrying said forms, after typing, while others are imperforate and continuous to reinforce the web and are separable by the ordinary shearing knife.

Typing of this kind may be conveniently 10 done on multiple-ply paper-webs, the plies being sometimes separate, but more generally connected in the form of a fan-fold web and having suitable forms printed thereon, the forms being torn off from the main portion 15 of the web after typing, as set forth in the Wernery & Smith Patent, No. 1,132,055, dated March 16, 1915.

In some cases, it is desired, in making out such forms and simultaneous copies, to 20 have the heading and all the entries or typed items appear on the original record-bill, to substantially form a condensed record and duplicate copies thereof, while only the heading and certain distinctive single items of said entries appear on said miscellaneous other bills or forms. Such an arrangement is especially convenient for a mercantile establishment, such as a mail-order house, when making out an order or bill 25 for a miscellaneous lot of goods, which is of such a variety as to necessitate the order being split up, so that the different items thereof may be conveniently sent to different departments for execution. As each item 30 of a bill of goods generally occupies only a single line of typing, it has been found difficult to type the split orders or bills at the same time that the original record-bill and duplicate copies are typed upon the fan-fold forms. This is because there must be 35 typed upon said record-bill and its duplicate copies a complete schedule of the items, whereas usually there must be typed upon each of the split-order bills only a single item. It is therefore one of the features of 40 the present invention to overcome this difficulty and enable each individual item to be typed singly upon its own separate form simultaneously with the typing of a group of 45 the same items upon the original record-bill and the duplicates thereof.

According to one form of the present invention, a front carbon-carrier of a continuous billing machine controls carbon-sheets

interleaved between the plies of the duplicate copies, and also a carbon which lies between the outermost or original ply and the top ply of a number of split-order forms interposed between said duplicate copies and the outermost ply. A rear carbon-carrier 55 controls carbons which are interleaved between the plies of the split-order forms. In typing upon such plies, both of the carbon-carriers have their respective carbons carried forward with the webs to the printing line, and, upon actuating the type, a heading may be written on all of the sheets. The carbons interleaved between the split-order plies are then withdrawn, and the platen may be line-spaced to bring the forms 60 to position for printing the first item simultaneously upon the original form or bill and duplicate copies thereof, and also upon only the first split-order form. The platen is then turned so as to bring all of the webs 65 upwardly, and the front sheet and its carbon are thrown forwardly so as to permit the first split-order form to be removed from its ply by tearing the same off along a line 70 of perforations provided for the purpose. The sheets may then be run to the printing line of the second item to be typed, and the same process as described in connection with the first split order is carried out on as 75 many forms as there are separate items to be typed. After all of the split-order forms have been removed from their plies, the remaining plies, that is, the original order and 80 duplicate copies thereof, are torn off from the main body of the web, against a cutting-off knife, and a new portion of the web is 85 brought forward to printing position.

The split-order plies are provided with transverse lines of perforations for weakening the connection between the adjoining 95 forms so that each form may be easily detached by the mere pulling of the form with the fingers without the aid of a knife. It will be apparent that if the transverse perforations were extended across the whole 100 web, the perforations would so weaken the web longitudinally as to make it too frangible for fan-fold work. It is well known that stripping the carbons places a great strain on the web and the liability of tearing the web at the perforations would render the web unfit for use in a typewriter.

In this invention, the web is only cross-

perforated in the inner plies thereof, the outer plies being smooth, thereby facilitating feeding of the web between the feeding rolls and the platen. The outer plies serve also as protecting guards for the fragile inner plies, thereby preventing accidental tearing of the inner plies when the web is handled roughly due to the high speed at which these machines are operated.

10 It will be understood that although it has been stated that each split-order form is individually removed from the machine after being typed upon, the last split-order ply is usually removed from the machine with the 15 combined order forms which are torn off against a knife. In view of this, it will be apparent that it is not necessary to provide the last split-order ply with cross-perforations. However, since the number of split 20 orders required from each bill is variable, the web is made with enough cross-perforated plies for the maximum number of split orders that at any time may be required.

This application is a division of my application filed November 4, 1924, Serial No. 25 747,726.

Other features and advantages will hereinafter appear.

In the accompanying drawings, 30 Figure 1 is a developed view of a fan-fold web such as may be used with the present invention.

Figure 2 is a view of a severed form, representing an original order-blank.

35 Figures 3, 4 and 5 represent split-order forms which have been severed from the main body of the web.

Figure 6 is a view of a fan-fold pack forming a portion of the web-unit.

40 Continuous forms or webs W are adapted to be used in a typewriting machine, such as shown in the patent to Wernery & Smith, No. 1,132,055.

In certain classes of work, such as in mail 45 order houses, orders are received which sometimes cover a great variety of goods and it is necessary that the order be split up and the different items thereof sent to the different departments for execution. For this purpose the web W consists of an outermost or original ply, designated by the reference letter "A", and a plurality of split-order plies or forms, designated by the letters "B", "C" and "D". Said split-order plies 55 occupy a position between the outer ply "A" and the fan-fold pack "E". A carbon carried on a forward carbon-carrier as shown in my original application, Serial No. 747,726, is interleaved between the outer or original 60 ply "A" and the split-order ply "B", and a rear carbon-carrier carries carbons which are interleaved respectively between the split-order plies "B" and "C", and "C" and "D".

65 By virtue of this arrangement the carbons

associated with the rear carbon-carrier may be readily withdrawn from their associated forms by moving the rear carrier rearwardly, after the headings have been printed upon all of the forms, and the original ply 70 or form will always remain the outermost one of the pack, so that it will invariably receive ribbon-impressions of typed matter.

Referring to Figure 1, which represents a developed view of fan-fold stationery such 75 as may be used in the present invention, it will be noted that the folding edges of the several plies comprising the web-unit are perforated at 10, so that they may be readily severed from one another. It will also 80 be noted that the split-order forms or plies indicated by the letters "B", "C" and "D" are perforated at 11 along their upper and lower margins, so as to permit each of the forms to be readily severed from its ply 85 after typing. As the web is drawn forwardly of the machine and around the platen, the side edges of the sheets "A", "B", "C" and "D" are severed along their side edges, by splitters carried on the carbon-carriers, while the side edges of the fan-fold pack "E" remain unsevered. After having 90 printed the headings on all of the plies, and withdrawing the carbon-sheets associated 95 with the plies "B", "C" and "D", by moving the rear carbon-carrier rearwardly, the platen-frame is lowered and the sheets run to the printing line, so as to receive type-written matter corresponding to a first item 100 of an order. Due to the fact that there are no carbon-sheets now interleaved between the plies "B" and "C", and "C" and "D", no typed impressions will appear upon the split-order plies "C" and "D", but the split order "B", which lies immediately beneath the carbon of the original order form "A", will receive a typed impression, and also all 105 of the plies of the fan-fold pack "E". The platen is next turned, so as to roll the plies upwardly until the perforations 11 of the 110 ply "B" appear above the cutting-off knife. This portion of the ply is then torn off along said perforations 11, thus removing the same in the form of an individual typewritten sheet, the original or outer ply "A" and its 115 carbon having been first folded over toward the front of the machine to permit easy access to the ply "B". The platen is now turned in the opposite direction, so as to bring the sheets down to the second line of 120 printing. The original sheet "A" and its carbon now overlie the split-order ply or form "C", and, upon operation of the type, the second item of the original ply or form "A" is typed thereon, and also upon each 125 ply or form of the fan-fold pack "E". The same cycle of operations is now carried out to remove the sheet "C" from the pack, and the platen advanced to print the third item. Thus it will be seen that the form "A" and 130

the individual plies of the fan-fold pack "E" receive a composite schedule of the typed items appearing on each of the split-order forms, and that each of the latter has 5 typed thereon only a single item, representing an order, which may be conveniently sent to its particular department for execution.

It will be seen that the full order is typed 10 line by line upon one form, and, at the same time, each line is typed upon a separate split-order form, there being numerous split-order forms, since each one is to contain only one item and the order may be 15 made up of half a dozen or perhaps a dozen items. It is shown, for illustration, that the order is made up of three items, but it is obvious that in practice each order is apt to be made up of any number of items. The 20 invention thus includes a collation of superposed plies, of which the top one constitutes a form for the typing of the full order thereon, line by line, in the manner of a condensed record, while the others consist of 25 split-order coupons upon each of which is manifolded only one item. This manifolding upon the superposed coupons is done by only one carbon-sheet. When the top coupon is being manifolded, nothing is done 30 upon the underlying coupons. When the second coupon is being manifolded, nothing is being done upon the first coupon nor upon the remaining underlying coupons. When 35 the third coupon is being manifolded, nothing is done upon the first two coupons. Hence, each of the coupons finally contains individually an item which is split off from the main order, the items being different upon the different coupons. For this purpose, the coupons form a part of the same 40 cross-section of fan-folded web with the main order form; and, after the typing of each line, the coupon upon which said line is typed is plucked out of the web without 45 mutilation, this operation being permitted because the coupons are joined to the remainder of the web by friable lines of connection. Heretofore, a transverse section of 50 web, having the same typing upon each ply as upon all the others, has been torn off by means of an implement; but a coupon has not heretofore been severed while leaving intact in the machine forms which constituted a part of the same transverse section of the 55 fan-fold web.

Variations may be resorted to within the scope of the invention, and portions of the improvements may be used without others.

Having thus described my invention, I 60 claim:

1. A continuous billing work-sheet web

for use in simultaneously printing with a typewriting machine an original record bill having a plurality of items entered thereon and a plurality of split bills each having a 65 single item entered thereon, comprising a wide web foldable into a plurality of fan-fold plies, the web having perforated lines extending longitudinally thereof between the edges of all the plies, the web also having successive printed forms in vertical and horizontal alignment, the web also having perforated lines extending from the ply on the left side of the web horizontally across a plurality of plies between the printed 75 forms, the side plies being imperforate. 70

2. A continuous billing work-sheet web for use in simultaneously making an original record bill having a plurality of items entered thereon and split bills each having a 80 single item entered thereon, comprising a wide web foldable into a plurality of fan-fold plies adapted to receive carbon sheets between each two plies, the longitudinal side edges of said plies being weakened by perforated lines extending longitudinally of the plies, the plies having similar printed forms in horizontal and vertical alignment when the web is spread out, the successive printed forms lying on opposite sides of the plies, 85 the web having perforated lines extending transversely thereof and stopping before they reach the side plies. 90

3. A fan-folded web for manifolding use in typing a plurality of items on a record- 95 bill and a plurality of superposed order-distributing coupons, the top fold of said web formed of a repetition of bills, the middle folds of said web formed each of a repetition of order-distributing coupons, and 100 the bottom folds of said web formed each of repetitions of bill-copies, the bill-forms and the order-distributing coupons being in horizontal alignment across the web, and the web having pluck-out lines of perforations 105 ending short of the outside series of forms for enabling each order-coupon to be plucked out of the web individually after it is typed, to expose the underlying order-coupon for typing the succeeding line 110 thereon, each transverse row of coupons being separated from the next transverse row by certain of said pluck-out lines of perforations, and the web being longitudinally 115 perforated at the folds. 115

4. Fan-folded web as recited in claim 3, in which the plies of the bill-forms and the plies of bill-copies are all imperforate transversely, to form the continuous unperforated plies, preventing excessive weakening 120 of the fan-fold pack.

JESSE A. B. SMITH.
